UNITED STATES PATENT OFFICE.

J. J. PARKER, OF MARIETTA, OHIO.

PAPER-FILE.

Specification of Letters Patent No. 26,285, dated November 29, 1859.

To all whom it may concern:

Be it known that I, J. J. PARKER, of Marietta, in the State of Ohio, have invented a new and useful Expansive Book-Back or 5 Paper-File; and I do hereby declare the following to be a correct description of the same, reference being had to the accompanying drawings, in which—

Figure 1 is an elevation of the interior of 10 the back with the spring bars closed; Fig. 2 is an elevation of the exterior of the back; Fig. 3 is an elevation of the back and covers with the hinge open; Fig. 4 is a horizontal section on the line x, x , of Fig. 1; and Fig. 5 15 is a horizontal section on the line z, z , of Fig. 3.

The nature of my invention consists in placing a hinge down the middle of a book back, and arranging within a back thus 20 hinged, a pair of spring bars, in combination with two or more pointed file wires, for the purpose of receiving and filing in a neat, compact, and convenient form, pamphlets, periodicals, documents, or other papers that 25 it may be desired to preserve, all as herein-after more particularly set forth.

To enable others to make and use my improved file, I will proceed to describe its construction and the manner in which it is 30 to be used, referring to the drawings, where the same part is marked by the same letter of reference, in all the figures.

A marks the body of the back; B, the line at which the back is hinged; C, the covers; 35 D, D', the parallel spring bars; E, the springs; F, the pointed file rods or wires; G, the back button.

a marks the pivot of button G; b, the hinges between the back and the covers of 40 the book; c, the slots or notches in bar D', for the reception of the rods F.

The back A, which is made strong and substantial, is hinged down the middle, on the line B B, so as to be capable of opening 45 backward. The button G, when turned across the back, renders it rigid; but when turned at right angles to that position, allows

the back to open on its hinge. The book covers C, are hinged to the back in the usual way. Inside the back, are placed the two 50 bars D, D', which are forced toward each other by the springs E. These bars move in guides at the top and bottom of the back. The bar D, has two holes in it, through which pass the pointed file rods F; and the 55 bar D' has two notches c, into which said rods are received when the back is closed. The two bars can be forced back against their springs, until nearly all the space between the covers is open for the reception 60 of the matter to be filed.

The operation is as follows: When it is desired to file a paper, the button G is turned into the position which allows the back A to open on its hinge B. This brings the 65 pointed rods F into a position to receive the paper, as clearly shown in Fig. 5. The paper or pamphlet is forced onto the pointed rods, and pressed into contact with bar D; when the back is closed; and the button G 70 turned to keep it so. The points of the rods are received into bar D'; and the filed paper is securely held by the united effect of the rods and the spring bars.

To give a neat finish to the article, the 75 bars and springs may be concealed from view by a covering of cloth, and the top and bottom of the back may be covered by an elastic fabric which does not interfere with its being opened on its hinge when required. 80

Having thus fully described my invention, what I claim and desire to secure by Letters Patent, is—

The combination with a hinged book back, 85 of bars, springs and rods, arranged for conjoint operation substantially in the manner described.

The above specification signed and witnessed this second day of November 1859.

J. J. PARKER.
